Attorney

UNITED STATES PATENT OFFICE.

SIMEON S. JACKSON, OF HYDE PARK, MASSACHUSETTS, ASSIGNOR TO THE STAFFORD COMPANY, OF READVILLE, BOSTON, MASSACHUSETTS, A CORPORATION OF MASSACHUSETTS.

TRANSFERRER FOR WEFT-REPLENISHING LOOMS.

Application filed November 11, 1925. Serial No. 68,324.

The invention is designed for employment in looms of the class in which weft replenishment is effected through automatic insertion of a reserve bobbin or other weft-carrier or filling-carrier, loaded with weft or filling, into the working shuttle of a loom, with simultaneous ejection of the spent or failed carrier previously occupying the shuttle.

- 10 The invention has relation to the so-called transferrers, sometimes termed hammers, by which a fresh or reserve weft or filling-carrier is driven into a working shuttle with resulting ejection of the spent or failed carrier. In practice, a transerrer or hammer is constructed with a head-portion which in operation strikes downward upon the top of the head of the carrier that is about to be placed in the shuttle, and in some cases it is provided with a striker-block that is disposed at a short distance transversely from the said head-portion and arranged to act against the periphery of the wound mass of weft or filling upon the carrier to ensure 25 that the whole length of the carrier, including its tip-portion, shall become entered fully into the shuttle.

The invention provides in novel manner for mounting a striker-block in connection 30 with the arm of a transerrer or hammer, with facility for adjustment of the said striker-block laterally, so that it may be arranged to strike against the wound mass of weft or filling at the required place in 35 the length thereof, and also with capacity for angular adjustment.

Illustrative embodiments of the principles of the invention are shown in the drawings. In the latter,—

- 40 Fig. 1 shows in side elevation a transerrer or hammer having an embodiment of the invention applied thereto.

Fig. 2 is an elevation of the rear end of said transerrer or hammer, looking from 45 the right-hand side in Fig. 1, a bobbin loaded with weft or filling, and a portion of a shuttle, being shown also.

Fig. 3 is a plan view of the parts which are shown in Fig. 2.

- 50 Figs. 2 and 3 illustrate the head 1 and striker-block 2 of a transerrer or hammer in the relations with respect to a bobbin 3 loaded with weft or filling 4 which they assume in the operation of driving such bobbin

into the working shuttle 5 of a weft-replenishing loom. As indicated in Fig. 1, the said head and striker-block are at the rear end of the transerrer-arm 6, the said arm extending rearward from the sleeve or hub 7 by means of which the transerrer or hammer is mounted upon a supporting-stud in a loom. The head 1 is furnished with a pin 8 projecting transversely outward therefrom, and striker-block 2 is mounted upon the said pin.

In the illustrated instance the striker-block 2 is formed with vertical cheek-portions 21, 21, and with a recess 22, Fig. 2, between them extending from front to rear. Holes 23, Fig. 1, are made in said cheek-portions, transversely therethrough, these holes accommodating pin 8 and permitting the striker-block to be mounted upon such pin. Within the recess is located a stirrup 9, in this instance annular, encircling the pin 8 and having a screw-threaded upstanding stem 91 which projects above the top of the striker-block, where it receives a washer 92 bridging the recess 22 and resting upon the top ends of the cheek-portions 21, 21, of the striker-block, and a nut 93 contacting with said washer. When the nut is slackened off the striker-block may be adjusted transversely upon the pin 8, toward or from the head 1, or may be adjusted angularly by being swung around the pin. When the nut is tightened up, the under part of the stirrup is caused to engage with the underside of pin 8 and the tops of the walls of the holes 23 are caused to engage with the top of said pin, thereby clamping the striker-block to the pin in the place and position into which it has been adjusted.

As will be perceived, the form and arrangement of parts admit of being modified more or less without departure from the essential principles of the invention.

What is claimed as the invention is:—

1. The combination comprising a transerrer or hammer of a weft-replenishing loom, a pin extending outward therefrom, a striker-block having a hole or holes therethrough occupied by the said pin, a stirrup engaging with the pin, and means combined with the striker-block and the stirrup for tightening the latter against the pin.

2. The combination comprising a transerrer or hammer of a weft-replenishing

loom, a pin extending outward therefrom, a striker-block having cheek-portions separated by a recess, with holes in said cheek-portions occupied by the said pin, a stirrup occupying said recess, engaging with the pin and extending upward, and means combined with the upward extension and with the top of the striker-block for tightening the stirrup against the pin and thereby securing the striker-block in adjusted position.

3. The combination comprising a trans-

ferrer or hammer of a weft-replenishing loom, a pin extending outward therefrom, a striker-block having cheeks separated by a recess, with holes in said cheeks occupied by said pin, an annular stirrup occupying said recess, encircling the pin, and having a screw-threaded stem, and a nut applied to said stem and adapted to tighten the stirrup to clamp the block in adjusted position 20 on the pin.

SIMEON S. JACKSON.
